CONNECTER

Temlinson Fort Johnson, Atlanta, Ga.

Application June 26, 1928. Serial No. 238,518

4 Claims. (Cl. 173—273)

This invention relates to connectors or line tapping devices and aims, among other objects, to provide an improved clamp and manipulating means therefor to insure that the connector may 5 be positively controlled by the operator while it is being connected to or disconnected from a live conductor.

In the accompanying drawing,

Fig. 1 is a side elevation showing one embodiment of the invention;

Fig. 2 is a side elevation taken at right angles to Fig. 1;

Fig. 3 is a sectional view taken on the line 3—3 of Fig. 2; and

Fig. 4 is a top plan view of the connector shown in Figs. 1 and 2.

Referring particularly to the drawing and to that form of invention shown for illustrative purposes therein, there is provided a bracket 20 member 10 having a socket 11 for the usual branch conductor 12 leading to apparatus to be tapped in. The under-face of the bracket has a shallow groove 13 adapted to receive a conductor 14 to afford a good electrical contact. 25 The upper face of the bracket 10 preferably has a reinforcing boss and a rib 15 extending from the socket member 11. Also, the lower face of the bracket is preferably machined and presents a downwardly extending lip or flange 16 30 to prevent the bracket from slipping off a conductor after it is hooked on.

Herein, the bracket has a screw threaded opening to receive a screw 17 carrying a clamping member 18, conveniently in the form of a machined disk, cooperating with the under-face 35 of the bracket 10 to clamp the conductor 14 in the shallow groove. The conductor, when it lies in the groove, prevents the bracket from rotating while the clamping member is being turned.

40 To connect and disconnect the clamp from the conductor, and to enable the operator to manipulate the bracket from a distance, the screw 17 is shown as extending through the clamping disk 18 to present a shank 19 having a groove 45 20 so that it may be engaged by a socket member 21 on an insulating handle or manipulating rod 22. In the present example, the disk 18 has an integral nut or non-circular head 23, the whole being preferably cast on the screw shank 50 and the socket member 21 presents a socket wrench 24 to engage the nut.

The arrangement is such that the operating member may be snapped on the shank 19 of the screw with the wrench engaging the nut, 55 the strength of the snap fastener element being

such as to prevent the socket member from slipping off due to a slight pull on the manipulating rod or handle. Herein, the snap fastener element cooperating with the groove 20 is shown as comprising a plunger pin 25 extending 60 through a hole in the side of the socket member and having a rounded end cooperating with the groove 20. The outer end of the pin is shown as having a head 26 with which the upper end of a leaf spring 27 fastened to the lower end of 65 the socket member engages. As will be seen in Fig. 3, the groove 20 and the end of the shank below the groove, are so shaped that the socket member may be engaged with and disengaged from the groove by a push or a pull. 70

When the connector is clamped tightly on a conductor, it is sometimes rather difficult to unscrew the clamping disk. To enable the bracket member to be held against rotation while the clamping member is being operated, the bracket 75 is shown as having an ordinary hook eye 28 adapted to receive a switch-hook or the hooked end of an ordinary hook stick such as is commonly used in transmission line work.

Inasmuch as the connectors are usually exposed to the weather, it is highly important that they be made of non-corrosive materials. To this end the bracket, the socket member and the clamping disk are preferably made of manganese bronze; while the screw 17 is preferably 80 made of Monel metal because this metal has adequate strength and will not corrode. The spring member 27 may be made of any non-corrosive spring material. However, it has been found that phosphor bronze is well adapted for 85 90 this purpose.

From the foregoing description, it will be seen that a connector may be very quickly and easily applied to a conductor and that the operator can control its application. The screw 17 fits 95 its threaded opening sufficiently snugly to prevent the bracket member from swinging around loosely on it. Before the connector is applied the clamping disk is opened sufficiently to permit the conductor to be slipped in between the 100 lip 16 and the top of the disk. As soon as the conductor engages in the groove 13, the screw is rotated by the socket wrench firmly to clamp the conductor between the machined face of the disk 18 and the bottom of the groove. When the 105 connection is being made, the branch conductor 12, will, of course, be bent so that the operator will not be in any danger of coming in contact with it. After the connector is thus clamped and placed on the conductor, the operator can 110

easily jerk off the socket wrench by pulling on the handle and disengaging the snap fastener.

- It has been found in practice that the improved connectors afford much better contact with conductors than the ordinary spring clamps because the disk rubs and slightly abrades the surface of the conductor and cleans it as the clamping screw is being turned to tighten it. Furthermore, they can be manipulated by an unskilled lineman without any danger. Further, the operator loses no time in engaging the manipulating member. Moreover, they can be clamped on a conductor in any angular position with respect to the conductor.
- 15 Obviously, the present invention is not restricted to the particular embodiment thereof herein shown and described.

What is claimed is:

1. A connector of the class described comprising, in combination, a bracket member having an arm presenting a grooved under-face to receive a conductor, a lip on the bracket adjacent to the groove; a screw threaded through the grooved face of the bracket member; and a clamping disk rigidly secured to the screw and adapted to clamp the conductor between its upper face and the bottom of the groove.
2. A connector of the class described, comprising, in combination, a bracket member adapted to be hooked over a conductor, a screw clamping member associated with the bracket member; a non-circular head on the screw clamping member; a grooved shank extending beyond the

head; a socket wrench engageable with the head and adapted to be slipped over the shank; a pin extending through the socket and engageable with the groove in the shank; and an insulating handle for operating the wrench.

80

3. A connector for charged conductors comprising, in combination, a bracket member having a conductor engaging portion; a screw carrying a clamping member connected to the bracket and cooperating with the conductor engaging portion to grip the conductor; an extension on the clamping member having a head to be engaged by an insulated manipulating implement; and said extension having a peripheral groove constituting a snap fastener element to be engaged by the manipulating implement and thereby hold the manipulating implement in operative engagement with the head.

85

4. A connector of the class described comprising, in combination, a bracket member having a conductor clamping member adapted to engage a conductor, said clamping member having a groove in its face to receive the conductor; a screw threaded through said bracket having an integral disk engageable with the conductor and cooperating with said bracket to clamp the conductor in said groove; a non-circular operating head on the screw adjacent to said disk; and a snap fastener element carried by the screw clamping member whereby to hold an operating member in operative engagement with said non-circular head.
